VALVE OPERATING MECHANISM

Edward J. Fitz, Fairfield, Conn., assignor to Jenkins Bros., New York, N. Y., a corporation of New Jersey

Application April 12, 1938, Serial No. 201,594

13 Claims. (Cl. 172—239)

This invention relates to devices for opening and closing valves, and more particularly to valve operating mechanisms of the electrically actuated, automatically controlled type wherein manually operable means are also provided for opening or closing the valves in an emergency.

Although valve operators of the same general character as that of the present invention have been known to the art for some time, these prior devices have not proven entirely satisfactory from a practical standpoint because of various difficulties inherent in the particular mechanical and electrical arrangements proposed.

It is therefore one of the objects of the present invention to provide a valve operating mechanism of new and improved construction which will ensure efficient and dependable operation under all conditions and will be free from the defects of similar devices hitherto known.

Another object of this invention is to provide a valve operator of the electrically actuated type wherein novel means are provided for automatically opening the electrical supply circuit either when the valve reaches a predetermined point in its travel in either direction or when during its movement toward closed position torque of a predetermined value is built up in the power transmission line between the electric motor and the valve.

A further object of this invention is to provide a novel combination of travel limit and torque responsive means for controlling the supply of current to the driving motor of an electrically actuated valve operating mechanism.

Still another object of this invention is to provide an automatically controlled, motor driven valve operator of improved construction wherein there are incorporated both a positive drive from the motor to the valve during the valve opening operation, so as to ensure opening of the valve even though it may tend to stick to its seat, and a torque responsive yielding drive in the valve closing direction which effects proper seating of the valve regardless of wear in the cooperating valve and valve seat surfaces.

A still further object is to provide a motor driven valve operator with novel mechanical means for automatically opening the motor circuit when the torque applied to the valve moving mechanism exceeds a predetermined value.

Still another object of the invention is to provide a valve operator of the type normally driven by electrical energy with novel manually operable means for opening and closing the valve in an emergency.

Another object of this invention is to provide a novel valve operating mechanism which is structurally simple, economical to manufacture, durable, and dependable in operation.

5 These and other objects will appear more fully upon consideration of the description of the embodiment of the invention which follows. Although only one specific form of valve operator has been described and illustrated in the accompanying drawings, it is to be expressly understood that these drawings are for purposes of illustration only and are not to be construed as defining the limits of the invention, reference being had for the latter purpose to the appended claims.

In the accompanying drawings, wherein like reference characters indicate like parts throughout the several views:

Fig. 1 is a longitudinal section, with certain parts shown in full, taken through the axis of the drive shaft of one form of valve operating mechanism embodying the present invention, the elements being shown in the positions occupied thereby when the valve is closely adjacent its closed or seated position and when the manual operating means is disengaged;

Fig. 2 is an end view of the mechanism of Fig. 1, as seen from the right in the latter figure, with certain parts shown in section along the rotor axis of the driving motor;

Fig. 3 is a sectional view taken substantially on line 3—3 in Fig. 1 showing the form of connection between the main driving shaft and the valve gear;

Fig. 4 is an enlarged sectional view through the switch box taken substantially on line 4—4 in Fig. 1 with certain parts shown in full;

Fig. 5 is an end view of the switch box with the cover removed as seen from the left in Fig. 4;

Fig. 6 is a circuit diagram of the electrical equipment embodied in the valve operating mechanism of the present invention showing the positions of the various elements of said equipment when the mechanism is in the condition indicated in Fig. 1;

Fig. 7 is a plan view of the sliding cam sleeve of the manually actuatable emergency operating means; and

Fig. 8 is a fragmentary sectional view of a portion of the manually actuatable operating means of Fig. 1 showing the elements thereof in operative position.

Referring first to Figs. 1, 2 and 3, the embodiment of the invention illustrated therein comprises an electric driving motor and its associ-

ated power transmission mechanism for normally operating a valve gear (the valve itself having been omitted from the drawings in the interest of simplicity), an arrangement of travel limit and torque responsive limit switches for controlling the supply of current to the motor, and manually actuatable means normally inoperative but operable in the event of an emergency for opening and closing the valve. As shown, the main drive shaft 10 of the device is journaled in suitable bearing bushings 11 and 12 which are mounted in bosses 13 and 14, respectively, of a two part, oil-tight housing 15. Oil may be added to or drained from housing 15 by removing plugs 16. Surrounding shaft 10 and secured to boss 13 of housing 15 as by threads 17 is a nut 18 designed to pack material 19 to prevent oil leakage along shaft 10 from housing 15. Packing nut 18 is secured against rotation by clamp and bolt 20. Shaft 10 is reduced in diameter as at 21, and secured thereto for rotation therewith as by key 22 is driving collar 23 which, as shown best in Fig. 3, is provided at one point of its periphery with an outwardly extending lug or finger 23'. Mounted for rotation upon shaft 10 and recessed to receive driving collar 23 is valve drive gear 24 which has a hub 25 extending outwardly along shaft 10. Slidably supported upon hub 25 is a sleeve 26, the inner end of which has an outwardly turned flange notched at one point on its periphery to receive and lockingly engage with a pin 27 which is slidably mounted in gear 24. Pin 27 normally extends inwardly into the recessed portion of gear 24 sufficiently to engage the finger 23' of driving collar 23 in the manner indicated in Fig. 3.

The outer end of sleeve 26 is recessed as at 28 to receive a spring 29 the inner end of which normally urges the sleeve to the left as seen in Fig. 1 so as to bring the flanged end thereof into contact with drive gear 24, the outer end of spring 29 abutting against spring rest 30 mounted in a recessed portion 31 of hub 25 and held in position by cap 32 which is suitably secured to hub 25 of gear 24, as by a set screw 48. Mounted for rotation on sleeve 26 is liner 33 upon which is mounted hub 34 of hand wheel 35, said liner and hub being secured together by a locking pin 36. Oil or grease may be admitted to this assembly through any suitable lubricating fitting 37.

Hub 34 of hand wheel 35 is enlarged and recessed as indicated at 38 to provide a housing for the mechanism by which the hand wheel may be coupled to the valve gear 24 for manual operation. As shown, there is mounted in recessed portion 38 a plunger 39 urged outwardly by spring 40. A glass cover 41 held beneath clips 42 (Fig. 2) normally retains plunger 39 in its inward position (Fig. 1) against the action of spring 40. Plunger 39 is circumferentially recessed at 43 to receive finger 44 of cam member 45 which is designed to rotate about pin 46 and to engage cam slot 47 of sleeve 26 when the manually actuatable means are in operative position (see Figs. 7 and 8).

Within housing 15 shaft 10 is provided with shoulders 49 and 50, and with a portion 51 of lesser diameter than shoulder 50 having a pair of diametrically opposite spiral grooves 52 formed in the surface thereof. The shoulder 49 abuts 70 against bearing bushing 11 and prevents movement of the shaft 10 outwardly to the right, as viewed in Fig. 1. Mounted for both rotation and longitudinal movement upon portion 51 is a sliding sleeve 53 normally 75

urged against shoulder 50 by a spring 55 which acts through a ball thrust bearing 54 against an internal shoulder 56 of sleeve 53 at one end and against an adjustable collar or nut 57 threaded to shaft 10 at the other. Mounted upon sleeve 53 is worm gear 58 the latter being partially supported by ball bearings 59 engaging shoulders 49 and 50 of shaft 10 and partially by a bearing bushing 60 housed in a boss 61 formed integrally with housing 15. The outside surface of sleeve 53 is provided with a pair of diametrically opposite, axially extending projections or keys 62 (see Fig. 2) which are adapted to be slidably received in corresponding grooves or keyways 63 formed interiorly of worm gear 58. Fixed with respect to each key 62 adjacent the right end thereof (as viewed in Fig. 1) and extending radially inwardly is a pin 64 on the inner end of which is rotatably mounted a shoe 65, these 20 shoes being so formed as to have a sliding fit within the grooves 63 of portion 51 of the shaft 10. With this construction, the worm gear 58, sleeve 53 and portion 51 of shaft 10 are so connected to one another that, at all times when the device 25 is operating in valve opening direction, and whenever the torque in valve closing direction is less than a predetermined value, all three of said elements rotate together; however, should the resistance to rotation of the shaft 10 in valve closing direction increase beyond the predetermined value (as determined by the helical angle of slots 52 and the force of spring 55), the worm gear 58 and sleeve 53 will rotate together through a limited angle relatively to portion 51 of the shaft 30 35 10 while at the same time the sleeve 53 slides axially to the left as viewed in Fig. 1 relatively to both the worm gear 58 and shaft 10 so as to actuate the torque limit switch means next to be described.

Connected to sleeve 53 for longitudinal or axial movement therewith, but unconnected thereto in so far as rotation of the sleeve is concerned, is a torque rod 67 which passes through the wall of housing 15 into a switch box formed by said 45 wall and a cover 68 detachably connected to the housing 15, an oil-tight joint being made around the rod 67 by a nut 69 and packing 89. Torque rod 67 carries at its outer end an adjustable switch tripping head 70 and lock nut 71, said head being adapted to contact the tail of a combined travel and torque limit trip 72 which is secured to a shaft 73 rotatably supported in arms 74 and 75 of housing 15. Also journaled in arms 74 and 75 is a second trip shaft 76 upon which is fixed travel limit trip 77. The arm 75 also provides support for a channel member 78 secured thereto in any suitable manner as by screws 79. The channel member 78 forms a rotation-preventing guideway for a pair of adjustable travel limit tripping nuts 80 and 81 which are mounted upon a left-handedly threaded portion 82 of a travel limit switch shaft 83. Shaft 83 is rotatably carried within the longitudinal center bore 84 of shaft 10 and is fixed at its end opposite to threaded portion 82 to the cap 32 by a pin 85. The bore 84 of shaft 10 is increased in diameter at 86 to receive a bearing member 87 for shaft 83, packing material 89, and a spring 88 adapted to compress the packing and seal the bearing against the leakage of oil outwardly into the switch box.

The normal driving power for the device is provided by an electric motor of any suitable character mounted in a housing 90 and having field coils 91 and an armature 92 mounted on a

vertical shaft 93. Shaft 93 is rotatably supported in suitable bearings 94 and 95 carried by the housing 90 which, as shown, may be formed integrally with one of the sections of the two part housing 15. Secured to the lower end of shaft 93 for rotation therewith, as by a key 86 and nut and cotter pin 87, is a worm 88 in driving engagement with worm gear 58.

Referring now to Figs. 4 and 5 wherein are shown the torque and travel limit trip assembly and associated switches mounted in the switch box beneath cover 66, it will be seen that the combined travel and torque limit trip 72, which is fixed to the shaft 73 by a clamp and bolt 99, is so formed as to be capable of operation by either the tripping head 70 of torque rod 67 or the travel limit tripping nut 80 of shaft 93. Trip 72 also has an extension 100 carrying an adjustable stop screw 101 which engages a suitable portion of arm 75 to limit the rotation of trip 72 and shaft 73 in a counterclockwise direction as seen in Fig. 4, this rotation being produced by a suitable spring 102 which surrounds shaft 73 with one end secured to arm 75 and the other thrusting against extension 100. Also secured to shaft 73 as by clamp bolts 103 and 104 are switch trip arms 105 and 106 carrying at their extremities adjustable trip screws 107 and 108 which are designed to engage leaves 109 and 110 of the two poles 111 and 112 of a combined torque and travel limit switch to open the same when the shaft 73 is rotated in a clockwise direction as seen in Fig. 4. The combined torque and travel limit switch may be of any suitable construction, but as here shown is of the double pole type, each pole comprising leaves 109 or 110 and 113 suitably spaced and insulated by a spacer 114 and secured to an insulating supporting member 115 by through bolts 116 and 117, the member 115 in turn being carried by a projection 118 formed integrally with and extending into the switch box from the end wall of housing 15.

As previously described, the travel limit trip 71, which is adapted to be contacted and moved by travel limit tripping nut 81, is secured to the second trip shaft 76 and is adapted to rotate said shaft in a counterclockwise direction when the valve reaches its predetermined limit of movement in the opening direction. Also mounted on shaft 76 are switch trip arms 119 and 120 carrying adjustable trip screws 121 designed to engage and open both poles 122 of a travel limit switch when the shaft 76 is rotated in a counterclockwise direction as seen in Fig. 4. The travel limit switch may be of any suitable construction, but is preferably of similar construction to the combined torque and travel limit switch having two poles each comprising leaves 123 and 124 suitably spaced and insulated by a spacer 125 and secured to the insulating supporting member 115 by the same through bolts 116 and 117 as are used for mounting the combined torque and travel limit switch. Also carried by shaft 76 is a spring 126 (Fig. 1), similar to spring 102, having one end secured to arm 75 and the other thrusting against travel limit trip 71 in such manner as to urge said trip and shaft 76 to rotate in a clockwise direction as seen in Fig. 4.

The electrical connections and controls of the valve operator of the present invention are diagrammatically illustrated in Fig. 6 wherein the driving motor is indicated at 90', 111 and 112 designate the two poles of the combined torque and travel limit switch adapted to be opened either by the tripping head 70 of torque rod 67

or by travel limit tripping nut 80 when the valve is seated or encounters excessive resistance when moving in the closing direction, and the poles of the travel limit switch operated by tripping nut 81 when the valve is open are designated at 122. As shown, the three-wire main supply circuit to the motor 90' is controlled by two sets of magnetically operated switches 131, 132, 133 and 137, 138, 139, the first set being actuated by a coil 135 energized through the circuit 145 when push button 128 is depressed to open the valve, while the second set is actuated by a similar coil 141 energized through the circuit 144 by closing the switch 127 when it is desired to move the valve toward closed position. Energy for both circuits 144 and 145 is derived from the main supply line through a suitable transformer 129, passing therefrom across the poles 111, 112 and 122, 122 of the limit switches and thence to the push button switches 127 and 128. In order to avoid the necessity for continuously holding down the push button switches 127 and 128 during the movements of the valve, the coils 135 and 141 are also adapted to close holding circuit switches 139, 134 and 138, 140, respectively, which maintain the current flow through said coils as long as the limit switches are closed by short circuiting the switches 127 and 128.

If desired, suitable signal lamps 142 and 143 may be connected across the circuits 144 and 145, respectively, in the manner illustrated in Fig. 6 to indicate the condition of the valve operating mechanism.

Considering now the normal mode of operation of the present device, and with particular reference to Figs. 1-6, let it be assumed that the device is properly adjusted and that the valve is approaching and closely adjacent to its seated or closed position. In this condition of the device both travel limit switch 122, 122 and combined torque and travel limit switch 111, 112 are in closed position under the influence of springs 102 and 126, while switches 136, 137, 138, 139 and 140 are held closed by coil 141 which is energized by current from the transformer 129 passing around the manual switch 127 through switches 138 and 140. The motor circuit is thus completed through switches 137, 138 and 139, and the armature 92 rotates shaft 93 and worm 88 in a clockwise direction (as viewed in Fig. 2) so as to drive the worm gear 58 in a similar direction. Rotation of worm gear 58 as described, acting through the keys 62, sleeve 53, shoes 55 and grooves 52 of the enlarged portion 51 of shaft 10, in turn rotates shaft 10, the spring 55 having sufficient force to hold sleeve 53 in the position shown in Fig. 1 in the absence of a torque in excess of a predetermined value. Rotation of shaft 10 also rotates driving collar 23 and, through the finger 23' and pin 21, valve gear 24. Rotation of valve gear 24 also acts through pin 21 to rotate sleeve 26 within the liner 33 and hub 34 of hand wheel 35, these elements being disconnected due to the fact that the cam member 45 is in its normal disengaged position. The movement of valve gear 24 is also transmitted through hub 25 and set screw 48 to cap 32 which in turn rotates travel limit switch shaft 83 in a clockwise direction through pin 85. Inasmuch as the portion 82 of shaft 83 is left-handedly threaded, clockwise rotation of said shaft moves the nuts 80 and 81 to the left, as viewed in Fig. 1.

As the valve starts to seat, the resistance to rotation of valve gear 24 and shaft 10 increases

and the torque load transmitted through sleeve 53, shoes 65 and grooves 52 becomes greater. When this load becomes sufficiently large to overcome the force of spring 55, relative rotation between the worm gear 58 and shaft 10 takes place with the result that the sleeve 53 is moved to the left (Fig. 1) against the force of spring 55 due to the cooperative action of shoes 65 and grooves 52. Movement of sleeve 53 to the left also moves torque rod 67 in the same direction and, as the valve becomes fully seated, brings tripping head 70 into contact with the tail of limit trip 72, rotating the latter in a clockwise direction (Fig. 4) against the action of spring 102, and opening the contacts of combined torque and travel limit switch 111, 112. Opening of limit switch 111, 112 opens circuit 144, deenergizes coil 141, and permits switches 136, 137, 138, 139 and 140 to open thereby breaking the supply circuit to the motor and bringing the device to rest.

As tripping head 70 engages the tail of limit trip 72, the nut 80, moving to the left on shaft 83 as above described, also closely approaches contact with said trip to insure opening of the combined torque and travel limit switch 111, 112 if, for any reason, the automatic torque responsive tripping mechanism should fail to operate. In this connection, it will be noted that the threaded connection between tripping head 70 and torque rod 67 enables the parts to be properly adjusted so that, during normal operation of the device, opening of the motor circuit upon closing of the valve is effected automatically by the torque rod 67 and tripping head 70 just before the nut 80 reaches a position where it would contact and actuate limit trip 72.

When the valve is closed, combined torque and travel limit switch 111, 112 is open and travel limit switch 122, 122 is closed. To open the valve electrically, push button switch 128 is closed so as to energize coil 135 and close switches 130, 131, 132, 133 and 134, thereby sending current to the motor through switches 131, 132 and 133 and short circuiting the switch 128 through holding circuit switches 130 and 134. Closing the circuit to the motor through the switches mentioned reverses the direction of armature rotation and drives the worm 98 and worm gear 58 in a counterclockwise direction, as seen in Fig. 2. During the initial portion of the first revolution of worm gear 58 in this direction, said gear rotates relatively to shaft 10, the shoes 65 sliding in grooves 52 and the sleeve 53 moving to the right under the influence of spring 55 and returning to the position shown in Fig. 1. This movement of sleeve 53 also carries torque rod 67 to the right, moving tripping head 70 out of contact with limit trip 72 and permitting combined torque and travel limit switch 111, 112 to close under the effect of spring 102.

As soon as sleeve 53 abuts shoulder 50, a positive, non-yielding drive is effected between worm gear 58 and shaft 10, and the latter is rotated in a counter-clockwise direction. In view of the fact that, during closing of the valve, the finger 23' of driving collar 23 and pin 27 of valve gear 24 occupy the relative positions indicated in Fig. 3, it will be seen that upon reversing the direction of operation of the device the shaft 10 will make almost a complete revolution before the driving finger 23' engages the pin 27; in this manner an effective hammer-blow action is obtained which facilitates breaking of the valve 75

away from its seat even though it may have a tendency to stick thereto.

Rotation of valve gear 24 in a counter-clockwise direction moves the valve toward open position, and also, through hub 25, set screw 48, cap 32 and pin 85, rotates shaft 83 in a counter-clockwise direction. This rotation of shaft 83 feeds nuts 80 and 81 therewith to the right in Fig. 1 said nuts being restrained against rotation by the channel member 78. Motion of the several parts continues as above described until the valve reaches its fully open position. At this point nuts 80 and 81 have traveled to the right to a point where nut 81 has engaged travel limit trip 77 and has rotated the latter and shaft 76 in a counterclockwise direction (Fig. 4) against the action of spring 126 sufficiently to open travel limit switch 122, 122. Opening travel limit switch 122, 122 opens circuit 145, deenergizes coil 135, and permits switches 130, 131, 132, 133 and 134 to open thereby breaking the circuit to the motor and bringing the device to rest.

To close the valve electrically, push button switch 127 is closed so as to energize coil 141 through the combined torque and travel limit switch 111, 112 (this switch being closed even though travel limit switch 122, 122 is open), and to thereby close switches 136, 137, 138, 139 and 140. Closing of the latter switches in turn sends current to the motor through switches 137, 138 and 139 in such a manner as to produce clockwise rotation (Fig. 2) of the armature shaft worm 98, worm gear 58 and shaft 10, and short circuits push button switch 127 through holding circuit switches 136 and 140. Due to the construction previously described and illustrated in Fig. 3, the shaft 10 again makes almost a complete revolution before the driving finger 23' contacts pin 27 of valve gear 24 and hence starts the valve from its open position with a hammer blow action.

Rotation of the valve gear 24 in a clockwise direction then moves the valve toward closed position, and also rotates shaft 83 in the same direction, feeding nuts 80 and 81 to the left as viewed in Fig. 1. As nut 81 moves out of contact with travel limit trip 77, the latter and shaft 76 are rotated in a clockwise direction (Fig. 4) under the action of spring 126 so as to close travel limit switch 122, 122, thereby restoring the electrical circuits to the condition illustrated in Fig. 6. From this time on until the valve is closed, or until an excessive amount of torque is built up while the valve is moving toward closed position, the operation of the device is as previously described.

If, for any reason, the electrical means provided to operate the device should fail, the manually actuatable means shown in Figs. 1, 2 and 8 may be used. To place the hand wheel 35 in driving relation with valve gear 24, glass 41 is broken by any suitable means, as by a hammer 146 clipped to the hand wheel for this purpose, so as to permit the plunger 39 to be forced to the right in Fig. 1 by spring 40. This outward movement of the plunger 39 rotates cam member 45 in a counter-clockwise direction about pin 46 so as to urge the end of the cam into the slot 47 of sleeve 26, as shown in Fig. 8. If slot 47 is not opposite cam 45 when the plunger 39 is released, hand wheel 35 may be rotated in either direction until the cam registers with and enters the slot. When the elements occupy the positions shown in Fig. 8, the hand wheel 35 may be rotated in the proper direction to open or close the valve, as

desired, the hand wheel driving the valve gear 24 through cam 45, slot 47, sleeve 26 and pin 27. Due to the shape of cam slot 47 as shown in Fig. 7, initial rotation of hand wheel 35 and cam 45 in either direction after engagement of the cam and slot will cause the sleeve 26 to slide to the right in Fig. 1 against the action of spring 29 and to draw the pin 27 outwardly to such an extent that, when gear 24 is rotated thereafter, the pin will not engage the finger 23' of driving collar 23. With this construction, the manually actuatable means may be operated without driving back through the transmission normally operated by the motor. At the same time, however, it will be noted that manual rotation of gear 24 also rotates shaft 83 as above described so that the nuts 80 and 81 are moved, and limit switches 111, 112 and 122, 122 are opened and closed, appropriately and in such a manner that the switch mechanism will be in its correct position should the electrical actuating means thereafter be used to operate the valve. When it is no longer necessary to use the manual operating means, plunger 39 may be pressed to the left in Fig. 1 against the action of spring 46, thereby rotating cam 45 clockwise about pin 48 and disengaging it from slot 47, and a suitable piece of glass placed under clips 42 (Fig. 2) to retain the plunger in its inward position. Spring 28 then slides sleeve 26 to the left which in turn moves pin 27 into position for contact with the driving finger 23'.

There is thus provided by the present invention a valve opening and closing device of improved construction wherein are embodied novel means for automatically controlling the operation of an electrical motor for moving the valve to open and closed position, said means including both torque responsive and travel limit mechanisms so arranged and coordinated as to result in a device that will be efficient and dependable in operation under all conditions of use. There is also provided a new and useful mechanism for manually actuating a valve operator of the normally electrically driven type which is so constructed as to be operable independently of the elements constituting the normal drive between the motor and valve gear while at the same time it maintains correspondence between the condition of the travel limit control mechanism and the position of the valve. But insofar as the valve operating means disclosed herein involves alternatively operable manual means for opening and closing the valve, as in an emergency, the same is not claimed herein but in copending application Serial No. 431,304, filed February 17, 1942, as a continuation in part hereof.

While only one specific form of the invention has been described and illustrated in the accompanying drawings, it will be obvious that the invention is not limited to the exact structure shown but is capable of a variety of mechanical embodiments. Various changes, which will now suggest themselves to those skilled in the art, may be made in the form, details of construction and arrangement of the parts without departing from the spirit of the invention. Reference is therefore to be had to the appended claims for a definition of the limits of the invention.

What is claimed is:

1. In a valve operator of the class described, the combination of a driving motor, an electrical supply circuit for said motor, a drive shaft adapted to be rotated by said motor, valve drive means drivably associated with said drive shaft, means

including a gear member mounted on said drive shaft for transmitting torque from said motor to said drive shaft, and torque responsive means for controlling said motor supply circuit including a member interposed between said gear member and drive shaft and keyed to the former for rotation therewith and axial movement relatively thereto, and means operatively connecting said interposed member and drive shaft so constructed and arranged as to produce both rotation and axial movement of said member relatively to said drive shaft when the torque transmitted from said motor to said drive shaft exceeds a predetermined value.

2. In a valve operator of the class described, the combination of a driving motor, an electrical supply circuit for said motor, a drive shaft adapted to be rotated by said motor, valve drive means drivably associated with said drive shaft, means including a gear member mounted on said drive shaft for transmitting torque from said motor to said drive shaft, and torque responsive means for opening said motor supply circuit when the torque transmitted from said motor to said drive shaft exceeds a predetermined value including a sleeve member having at least a portion thereof housed within said gear member and operatively connected with both said gear member and said drive shaft, said sleeve member and its connections to said gear member and drive shaft being so constructed and arranged that the occurrence of an excessive torque produces a relative rotational movement of said gear and sleeve members with respect to said drive shaft and an axial movement of said sleeve member relative to both said gear member and drive shaft away from its normal driving position.

3. In a valve operator of the class described, the combination of a driving motor, an electrical supply circuit for said motor, a drive shaft adapted to be rotated by said motor, valve drive means drivably associated with said drive shaft, means including a gear member mounted on said drive shaft for transmitting torque from said motor to said drive shaft, and torque responsive means for opening said motor supply circuit when the torque transmitted from said motor to said drive shaft exceeds a predetermined value including a sleeve member having at least a portion thereof housed within said gear member and operatively connected with both said gear member and said drive shaft, said sleeve member and its connections to said gear member and drive shaft being so constructed and arranged that the occurrence of an excessive torque produces a relative rotational movement of said gear and sleeve members with respect to said drive shaft and an axial movement of said sleeve member relative to both said gear member and drive shaft away from its normal driving position, and yieldable means for resisting said relative movements of said gear and sleeve members until the occurrence of said excessive torque.

4. In a valve operator of the class described, the combination of a driving motor, an electrical supply circuit for said motor, a drive shaft adapted to be rotated by said motor, valve drive means drivably associated with said drive shaft, means including a gear member mounted on said drive shaft for transmitting torque from said motor to said drive shaft, and torque responsive means for opening said motor supply circuit when the torque transmitted from said motor to said drive shaft exceeds a predetermined value including a sleeve member having at least a portion thereof housed within said gear member and operatively connected with both said gear member and said drive shaft, said sleeve member and its connections to said gear member and drive shaft being so constructed and arranged that the occurrence of an excessive torque produces a relative rotational movement of said gear and sleeve members with respect to said drive shaft and an axial movement of said sleeve member relative to both said gear member and drive shaft away from its normal driving position, and yieldable means for resisting said relative movements of said gear and sleeve members until the occurrence of said excessive torque.

mined value including a sleeve member having at least a portion thereof housed within said gear member and operatively connected with both said gear member and said drive shaft, said sleeve member and its connections to said gear member and drive shaft being so constructed and arranged that the occurrence of an excessive torque produces a relative rotational movement of said gear and sleeve members with respect to said drive shaft and an axial movement of said sleeve member relative to both said gear member and drive shaft away from its normal driving position, a spring for yieldably resisting axial movement of said sleeve member in one direction, and means for positively preventing axial movement of said sleeve member in the opposite direction beyond its normal driving position.

5. In a valve operator of the class described, the combination of a driving motor, an electrical supply circuit for said motor, a drive shaft adapted to be rotated by said motor, valve drive means drivably associated with said drive shaft, means including a gear member mounted on said drive shaft for transmitting torque from said motor to said drive shaft, and torque responsive means for opening said motor supply circuit when the torque transmitted from said motor to said drive shaft exceeds a predetermined value including a sleeve member having at least a portion thereof housed within said gear member and operatively connected with both said gear member and said drive shaft, said sleeve member and its connections to said gear member and drive shaft being so constructed and arranged that the occurrence of an excessive torque produces a relative rotational movement of said gear and sleeve members with respect to said drive shaft and an axial movement of said sleeve member relative to both said gear member and drive shaft away from its normal driving position, a member mounted in a normally fixed axial position with respect to said drive shaft, and a compression spring operatively interposed between said last named member and said sleeve member for yieldably resisting axial movement of the latter out of its normal driving position.

6. In a valve operator of the class described, the combination of a driving motor, an electrical supply circuit for said motor, a drive shaft adapted to be rotated by said motor, valve drive means drivably associated with said drive shaft, means including a gear member mounted on said drive shaft for transmitting torque from said motor to said drive shaft, and torque responsive means for opening said motor supply circuit whenever the torque transmitted from said motor to said drive shaft exceeds a predetermined value including a cam groove formed in said drive shaft, a sleeve member interposed between said gear member and said drive shaft, means operatively connecting said sleeve and gear members for rotation together but permitting a relative axial movement therebetween, a cam follower member carried by said sleeve member and engaging said cam groove, said cam follower and groove providing a normally effective driving connection between said sleeve member and drive shaft but permitting a limited rotational and axial movement of said sleeve member relatively to said drive shaft, means yieldably resisting axial movement of said sleeve member out of its normal driving position, and means actuated by such axial movement of said sleeve member for opening said motor supply

75 circuit, said cam groove and yieldable resisting means being so constructed and arranged as to produce a relative rotational movement of said gear and sleeve members with respect to said drive shaft and an axial movement of said sleeve member relative to both said gear member and drive shaft when the torque transmitted from said motor to said drive shaft exceeds a predetermined value.

10. In a valve operator of the class described, the combination of a driving motor, an electrical supply circuit for said motor, a drive shaft adapted to be rotated by said motor, valve drive means drivably associated with said drive shaft, means including a gear member mounted on said drive shaft for transmitting torque from said motor to said drive shaft, and torque responsive means for opening said motor supply circuit whenever the torque transmitted from said motor to said drive shaft exceeds a predetermined value including a cam groove formed in said drive shaft, a sleeve member interposed between said gear member and said drive shaft and keyed to said gear member for rotation therewith and axial movement relative thereto, a cam follower member carried by said sleeve member and engaging said cam groove, said cam follower and groove providing a normally effective driving connection between said sleeve member and drive shaft but permitting a limited rotational and axial movement of said sleeve member relatively to said drive shaft, means positively preventing axial movement of said sleeve member in one direction beyond its normal driving position, a compression spring yieldably resisting axial movement of said sleeve member in the opposite direction, and means actuated by the axial movement of said sleeve member in said last mentioned direction for opening said motor supply circuit, said cam groove and spring being so constructed and arranged as to produce a relative rotational movement of said gear and sleeve members with respect to said drive shaft and an axial movement of said sleeve member relative to both said gear member and drive shaft when the torque transmitted from said motor to said drive shaft exceeds a predetermined value.

15. In a valve operator of the class described, the combination of a driving motor, an electrical supply circuit for said motor, a drive shaft adapted to be rotated by said motor, valve drive means drivably associated with said drive shaft, means including a gear member mounted on said drive shaft for transmitting torque from said motor to said drive shaft, torque responsive means for controlling said motor supply circuit including a sleeve member interposed between said gear member and drive shaft and keyed to the former for rotation therewith and axial movement relatively thereto, and means operatively connecting said sleeve member and drive shaft so constructed and arranged as to produce both rotation and axial movement of said sleeve member relatively to said drive shaft when the torque transmitted from said motor to said drive shaft exceeds a predetermined value during travel of the valve in valve closing direction, and travel limit means including a rotatable element coaxial with said drive shaft and drivably connected with said valve drive means for opening said motor circuit at a predetermined point in the travel of the valve in valve opening direction.

20. In a valve operator of the class described, the combination of a driving motor, an electrical

supply circuit for said motor, a hollow drive shaft adapted to be rotated by said motor, valve drive means drivably associated with said drive shaft, means including a gear member mounted on said drive shaft for transmitting torque from said motor to said drive shaft, torque responsive means including a sleeve member interposed between and operatively connected with both said gear member and drive shaft and movable axially relatively thereto for opening said motor supply circuit when the torque transmitted from said motor to said drive shaft exceeds a predetermined value during travel of the valve in valve closing direction, and travel limit means for opening said motor circuit at a predetermined point in the travel of the valve in valve opening direction including a threaded shaft passing through the bore of said hollow drive shaft and drivably connected to said valve drive means, non-rotatable means having threaded engagement with said threaded shaft for axial movement therealong, and means actuated by the axial movement of said last named means for opening said motor supply circuit.

10. In a valve operator of the class described, the combination of a driving motor, an electrical supply circuit for said motor, a hollow drive shaft adapted to be rotated by said motor, valve drive means drivably associated with said drive shaft, means including a gear member mounted on said drive shaft for transmitting torque from said motor to said drive shaft, torque responsive means including a sleeve member interposed between and operatively connected with both said gear member and drive shaft and movable axially relatively thereto for opening said motor supply circuit when the torque transmitted from said motor to said drive shaft exceeds a predetermined value during travel of the valve in valve closing direction, and travel limit means for opening said motor circuit at predetermined points in the travel of the valve in both valve opening and valve closing directions including a threaded shaft passing through the bore of said hollow drive shaft, non-rotatable traveler means having threaded engagement with said threaded shaft for axial movement therealong, and means actuated by the axial movement of said traveler means for opening said motor supply circuit, said torque responsive and travel limit means being so constructed and arranged relatively to each other that upon seating of the valve under normal conditions said torque responsive means are effective to open the motor supply circuit prior to movement of said traveler means to circuit opening position.

11. In a valve operator of the class described, the combination of a driving motor, an electrical supply circuit for said motor, a drive shaft adapted to be rotated by said motor, valve drive means drivably associated with said drive shaft,

5 torque responsive means for opening said motor supply circuit when the torque transmitted from motor to said drive shaft during movement of the valve in valve closing direction exceeds a predetermined value, and travel limit means also adapted to open said motor supply circuit when the valve reaches a predetermined point in its movement in valve closing direction, said torque responsive and travel limit means being so constructed

10 and arranged relatively to each other that upon seating of the valve under normal conditions said torque responsive means are effective to open the motor supply circuit prior to circuit opening operation of said travel limit means, leaving said last named means in operable condition to open said circuit in the event that said torque responsive means should fail to operate properly.

12. In a valve operator of the class described, 20 the combination of a driving motor, an electrical supply circuit for said motor, a drive shaft adapted to be rotated by said motor, valve drive means drivably associated with said drive shaft, a normally closed switch in said motor supply circuit, torque responsive means for opening said switch when the torque transmitted from said motor to said drive shaft during movement of the valve in valve closing direction exceeds a predetermined value, and travel limit means also operative to open said same switch when the valve reaches a predetermined point in its movement in valve closing direction, said torque responsive and travel limit means being so constructed and arranged relatively to each other that upon seating of the valve under normal conditions said torque responsive means are effective to open said switch prior to movement of said travel limit means to switch opening position, leaving said last named means in operable condition to open said switch in the event that said torque responsive means should fail to operate properly.

13. In a valve operator of the class described, 25 the combination of a driving motor, an electrical supply circuit for said motor, a drive shaft adapted to be rotated by said motor, valve drive means drivably associated with said drive shaft, a normally closed switch in said motor supply circuit including a tripping lever for opening said switch, torque responsive means including a member movable axially relatively to said drive shaft and adapted to engage the tripping lever of said switch for opening said switch when the torque transmitted from said motor to said drive shaft exceeds a predetermined value, and travel limit means including a second member movable axially relatively to said drive shaft and also adapted to engage said same tripping lever for opening said switch when the valve reaches a predetermined point in its movement.

EDWARD J. FITZ.
